UNITED STATES PATENT OFFICE

166,485

BRASSIÈRE

Morris Newman, New York, N. Y., assignor to Surprise Brassiere Co. Inc., New York, N. Y., a corporation of New York

Application August 4, 1951, Serial No. 16,149

Term of patent 14 years

(Cl. D20—4)

To all whom it may concern:

Be it known that I, Morris Newman, a citizen of the United States of America, and resident of the city, county, and State of New York, having invented a new, original, and ornamental Design for a Brassière, of which the following is a specification, reference being had to the accompanying drawing, forming a part thereof, and showing a front view of a brassière embodying my new design.

I claim:

The ornamental design for a brassière, as shown.

MORRIS NEWMAN.
